UNITED STATES PATENT OFFICE.

CHARLES H. ANDERSON, OF CINCINNATI, OHIO.

PUSH-BUTTON MECHANISM FOR PASSENGER-CARS.

1,178,374.

Specification of Letters Patent.

Patented Apr. 4, 1916.

Application filed January 21, 1915. Serial No. 3,609.

To all whom it may concern:

Be it known that I, CHARLES H. ANDERSON, a citizen of the United States, and a resident of Cincinnati, in the county of Hamilton and State of Ohio, have invented certain new and useful Improvements in Push-Button Mechanism for Passenger-Cars; and I do hereby declare the following to be a full, clear, and exact description of the invention, such as will enable others skilled in the art to which it appertains to make and use the same.

My invention relates to an improvement in push button mechanism for passenger cars.

Heretofore it has been the universal practice to mount the push button contacts directly on the side post capping of the car, the wire connections running down from the frieze to the push buttons. With steel car construction, wherein metal side posts and metal capping or pilaster for the same are employed, trouble frequently results from short circuits. Again the old method of installing the push button mechanism necessitated numerous wire connections, each of which is a source of possible trouble.

The object of my invention is to dispense entirely with wire connections between the push buttons and the wires carrying the current, and employ mechanical means actuated by the push button for closing the circuit through the wires carrying the current, the said latter wires being continuous throughout the car and without any permanent connection with the several push buttons, thereby eliminating all trouble caused by defective joints or connections.

In the accompanying drawings, Figure 1 is a view in section through a steel car showing my improvement installed therein; Fig. 2 is a view in horizontal section through a side post, showing the metal capping for the latter and the push button carried by the metal capping, and Fig. 3 is a view in section of the strip carrying the main wires, and the block carrying the metal finger which connects with said main wire when the push button is actuated.

1 represents the metal side post of a passenger car, 2 the curtain box and 3 a combined metal cap or pilaster and curtain and window frame guide secured to the inner or free edge of the web of the side post.

Located within the curtain box 2 is a wood strip 4, extending throughout the length of

the car and carrying the wires 5 which are connected up to a battery or other source of electricity and also to the bell. The wires are preferably located within grooves 60 formed in the bottom of a recess extending throughout the length of the strip 4, and are covered and concealed and protected by the strip 6 secured within said recess.

Mounted to move vertically within a slot 65 in the edge of the strip 4 adjacent the post 1, is the block 7, made of fiber or any other non-conducting material, and provided with a metal finger 8, which projects into a recess 9 formed in the strip 4, the said wires 5 passing through, and exposed within said recess 9 above the finger 8, so that when the finger is elevated, it will make contact with both wires 5, close the bell circuit, and ring the bell. The block 7 preferably terminates 70 at its top in the plane of the strip 4 and is held normally in its depressed position with its finger 8, out of contact with the wires 5, by the spring 10 secured to the top face of closure strip 6 and bearing at its free end 75 against said block. While the employment of the spring is desirable, it is not absolutely necessary, as the weight of the block 7 and its attached parts is sufficient to maintain the block in its normal position with its finger 8, out of contact with the wires 5. The block 7 is provided with a shoulder 10^a, which, when the block is in its normal position rests on the base board 11 of the window curtain box 2, and is yieldingly held on 80 the same by the spring 10.

Secured to and depending from the block 7, is the rod 12 which passes down within the sheet metal cap 3 of post 1, and rests at its lower end on the top ball or sphere 13 of 95 a series which is located within the curved bore of elbow 14. The lower end of said rod 12 projects into the upper end of said elbow a distance greater than it is moved vertically to carry finger 8 into contact with the wires 5, hence there is no possibility of dislodging the rod 12 by any movement that can be imparted to the push button. The elbow is clamped to the post cap or pilaster 3 by the screw sleeve 15, which is screwed onto the 100 exposed end of the elbow, which as shown projects through a hole in the cap or pilaster, and not only operates to lock the elbow in place, but also locks the push button 16 to the elbow with the finger 17 of the button in 110 line with the lower ball of the series of balls. The weight of the block 7, rod 12 and balls

13 normally hold the button 16 projected, and when the latter is pushed in to elevate the rod 12, it will return to its normal projected position as soon as the pressure is removed from the same.

5 While it not necessary that the rod 12 shall be attached to block 7, I prefer to so construct it, as there will then be no lost motion between the parts.

10 From the foregoing it will be seen that by pushing in on the button 16, the balls will be forced up the bore of the elbow and impart a lifting movement to the rod 12, which in turn lifts the block 7 until the finger 8 of the latter makes contact with the wires 5 thus closing the circuit and ringing the bell. By releasing the pressure on the button, the parts will drop back into normal position, and will be assisted in such movement by the 20 spring 10.

With my construction the wires carrying the current are continuous from end to end of the car without any permanent connection with any of the push buttons, thus 25 eliminating at least four joints for each push button and minimizing all chance for short circuiting.

It is evident that many slight changes 30 might be resorted to in the relative arrangement of parts shown and described without departing from the spirit and scope of my invention. Hence I would have it understood that I do not wish to confine myself to the exact construction shown and described, 35 but

Having fully described my invention what I claim as new and desire to secure by Letters Patent, is:—

1. In push button mechanism for passenger cars, the combination of current carrying wires, a circuit closing member normally held out of contact with said wires by gravity, a push button, and mechanical means movable at right angles to the movement of the 40 push button and connecting the latter with the circuit closing member, whereby when the push button is forced inwardly the circuit closing member will be moved into contact with the current carrying wires.

45 2. In push button mechanism for passenger cars, the combination of current carrying wires extending throughout the car, a circuit closing member normally held out of contact with said wires by gravity and adapted to be moved to engage both of said 50 wires, a vertical rod for actuating said member, a push button at right angles to said rod, and mechanical means intermediate the said rod and push button whereby the rod

will be moved vertically when the button 60 is pushed inwardly.

3. In push button mechanism for passenger cars, the combination of current carrying wires extending lengthwise the car, a vertically movable block carrying a finger 65 adapted when moved upwardly to contact with both of said wires and close the circuit through the same, a rod for lifting said block, a push button movable at right angles to said rod and means intermediate the push 70 button and rod whereby the latter may be actuated in one direction by the latter.

4. In push button mechanism for cars, the combination of two current carrying wires, a circuit closing member adapted 75 when moved upwardly to make contact with both of said wires, an elbow secured to the side of the car and having a curved bore, a push button carried by said elbow, a series of balls located within the bore of said elbow and a rod resting at one end on the uppermost of said balls, and its other end located in a position to lift the circuit closing member.

5. In push button mechanism for cars, the 85 combination of a strip made of non-conducting material, current carrying wires embedded within said strip, a circuit closing member located within a recess in the strip and below said wires and adapted to make 90 contact with the wires carried by said strip, a vertically movable rod for actuating said member, a push button movable in a plane at right angles to the movement of the rod and mechanical devices intermediate the 95 push button and rod whereby the latter may be moved vertically by the push button and the push button be moved outwardly by the weight of the vertically moving parts.

6. In push button mechanism for passenger cars, the combination of current carrying wires, a vertically movable rod, a circuit closer carried by said rod and adapted to make contact with the current carrying wires, a horizontally disposed push button, 100 and flexible connecting means intermediate the lower end of the rod and the inner end of the push button, whereby the inward movement of the push button elevates the rod and circuit closer carried by the latter. 105

In testimony whereof I have signed this specification in the presence of two subscribing witnesses.

CHARLES H. ANDERSON.
